UNITED STATES PATENT OFFICE.

ALBERT WIDMAN AND JOHN C. BAKER, OF CONNERSVILLE, INDIANA.

ROTARY ENGINE.

SPECIFICATION forming part of Letters Patent No. 633,631, dated September 26, 1899.

Application filed October 17, 1898. Serial No. 693,825. (No model.)

To all whom it may concern:

Be it known that we, ALBERT WIDMAN and JOHN C. BAKER, citizens of the United States, residing at Connersville, in the county of 5 Fayette and State of Indiana, have invented a new and useful Rotary Engine, of which the following is a specification.

Our invention relates to rotary engines, and has for its object to provide a simple and compact construction and arrangement of parts whereby an economical application of motive agent to the wings of a rotary piston may be attained; to provide a simple construction and arrangement of piston-wings and means 15 for folding the same successively as they pass the inlet-port of the casing, and, furthermore, to provide means for ascertaining and controlling the back pressure upon a piston-wing after passing the exhaust-port.

20 Further objects and advantages of this invention will appear in the following description, and the novel features thereof will be particularly pointed out in the appended claims.

25 In the drawings, Figure 1 is a side view of an engine constructed in accordance with our invention. Fig. 2 is a central sectional view of the same taken in a plane perpendicular to the axis of the piston. Fig. 3 is a central 30 sectional view taken in a plane parallel with the axis of the piston. Fig. 4 is a detail sectional view of a portion of the piston. Fig. 5 is a detail view in perspective of one of the piston-wings.

35 Similar numerals of reference indicate corresponding parts in all the figures of the drawings.

Rising from a suitable base 1 are pedestals 2, at the upper ends of which are arranged 40 bearings 3 for the piston-shaft 4, and secured to said piston-shaft is piston-core 5, operating in a casing consisting of a cylindrical wall 6 and opposite parallel heads 7.

The engine embodying our invention is of 45 the concentric-piston type, wherein a cylindrical piston-core 5 operates concentrically in the casing, and carried by this piston-core are radially-reciprocating wings 8, fitted in radial seats 9 and yieldingly held extended 50 by means of springs 10. We preferably dispose the springs, which are of the coiled type,

concentric with guide-pins 11, fixed to the piston-core at the inner ends of the seats 9 and extending outwardly into guide-openings 12 in the wings. Extending rearwardly from 55 each piston-wing is a web 13, having a rearwardly and inwardly inclined outer edge forming a cam-face, which in the extended position of the wing extends approximately from the outer edge of the wing to the cylindrical surface of the piston-core, and in large engines we preferably dispose a guide-pin 14 in operative relation with this web to operate in a guide-opening 15 and embraced by a coiled spring 16 for advancing the web outwardly with the wing to prevent cramping or binding, such auxiliary pin 14 and co-operating-spring 16 being illustrated in the drawings.

Secured to the opposite side surfaces of the 70 piston-core are side plates 17, of a diameter greater than the steam-chamber of the cylinder and having an interlocking connection with the cylindrical wall of the casing, said side plates or disks being rabbeted, as shown 75 at 18, to fit in rabbets formed in the cylindrical wall 6, with the outer surfaces of said disks in contact with the inner surfaces of the cylinder-heads 7. These disks may be secured by any suitable means to the piston-core, as by screws 19, and they form not only the means for maintaining the piston in a 80 truly-alined position with relation to the cylinder and relieve the piston-shaft 4 of a large proportion of the transverse strain due to 85 the operation of the mechanism, but they serve to prevent leakage of the motive agent by reason of the interlocking joint between their peripheries and the cylinder-wall. The disks 17 are provided in their inner or facing 90 surfaces with guide-grooves 20, alined with the piston-wing seats 9 to receive the lateral edges of the piston-wings, and thus insure the accurately-alined radial reciprocation of said wings.

In the construction illustrated the piston-shaft is shown extending outwardly through bearing blocks or brasses 21 in the cylinder-heads, and a belt or fly wheel 22 may be attached to said shaft as in the ordinary practice.

Communicating with the steam-chamber of

the chamber of the cylinder is an inlet or feed port 23, and contiguous thereto is the abrupt end of a piston-wing-folding cam 24, which tapers rearwardly from the inlet-port 5 to a point approximately diametrically opposite to said port, where the surface thereof merges into that of the cylindrical wall of the casing. The surface of this cam is tapped at an intermediate point for communication o with an exhaust-port 25 and also at a point near the abrupt end for communication with a relief or gage cock 26, and at its abrupt end the cam is provided with an antifriction bearing-roll 27 for contact with the peripheral 15 surface of the piston-core and the upper or outer edges of the piston-wing webs.

The inlet-port 23 communicates with a valve-easing in which is arranged an oscillatory or rocking valve 28, exposed to the 20 pressure of a motive agent, such as steam, admitted through the supply-port 29, and thereby held in efficient contact with the valve-seat. Said valve is loosely connected for radial movement with the cross-sectionally- 25 angular valve-stem 30, mounted in horizontally-lined bearings in the ends of the casing, and to one exposed extremity of said valve-stem is attached a crank-arm 31, from which extends an eccentric-rod 32 and an eccentric-strap 33, encircling an eccentric 34 on the main or piston shaft 4. In order to vary the throw of the valve to secure to a greater or less extent the effect of the expansive force of the motive agent, an adjustable connection is formed between the eccentric-rod and the crank-arm, such connection in the construction illustrated consisting of 35 a slot 35, engaged by a pivot-bolt 36.

The described mounting of the valve with 40 relation to the valve-stem allows radial movement of the valve as the contacting surfaces of the valve and valve-chamber become worn, and the pressure of the fluid contents of the chamber causes such movement to maintain 45 a steam-tight contact of the face of the valve with the wall of the chamber.

In operation the steam or other motive agent is admitted at intervals controlled by the oscillation of the cut-off valve to act upon 50 the rear or webbed surfaces of the piston-wings, back pressure of the steam or motive agent being received by the abrupt end of the cam 24, which constitutes a fixed abutment. As a wing traverses the surface of the cam 55 24 it is repressed in opposition to the tension of the extending spring 10 and also of the auxiliary spring 16 when the latter is employed, and after said wing passes the exhaust-port 25 all of the steam or motive agent 60 remaining in the steam-chamber is compressed and forced into the steam-chamber in advance of the fixed abutment, the relief-cock 26 being employed to ascertain the amount of compression. After the wing 65 passes the fixed abutment it is extended by the force of its actuating-springs, and the

rapidity of extension is controlled by the cam-faced web 13 with the antifriction bearing-roll 27 to avoid jar or other irregularity of motion.

It will be understood that by reason of the specific construction, particularly with reference to the interlocking connection between the piston-disks 17 and the walls of the casing or cylinder, the necessity for a plurality 75 of stuffing-boxes is avoided. Hence in practice we preferably arrange simple bearing-brasses 21, as hereinbefore described, in the heads of the cylinder to receive the wear of the piston-shaft, said brasses being adapted 80 by any suitable means for adjustment to take up lost motion due to wear. The only stuffing-box which is indispensable in connection with the apparatus as described is that shown at 37, through which extends the valve-stem. 85 Furthermore, the specific construction and arrangement of the piston-wings and guiding and controlling webs provide for accuracy of movement and prevent binding during rapid operation, and thus add materially to the efficiency 90 of the device. Furthermore, the compression of steam or air in advance of a piston-wing between the exhaust-port 25 and the gage-cock 26 serves to prevent waste or leakage of pressure rearwardly beyond the roller 95 27, and by opening the cock the operator may ascertain whether there is any loss of pressure at this point. A tight contact between the piston-core and roller 27 cannot be provided because allowance must be made for 100 expansion of the metal by heat, and if it is ascertained that the back pressure upon the piston-wings is excessive or is more than sufficient to resist the back pressure of the live motive agent past the roller 27 said pressure 105 in front of the piston-wing may be partly relieved by opening the cock more or less.

Various changes in the form, proportion, and the minor details of construction may be resorted to without departing from the spirit 110 or sacrificing any of the advantages of this invention.

Having described our invention, what we claim is—

1. In a rotary engine, the combination with 115 a piston-core, of spring-extended radially-movable wings mounted upon the core and carrying rearwardly-extending cam-faced webs for extension with the wings and adapted to traverse a fixed bearing object, where- 120 by the extension of a wing, after passing a fixed abutment, is accomplished gradually, substantially as specified.

2. In a rotary engine, the combination with 125 a piston-core provided with radial seats, of a piston-wing, provided with an extending spring, and having a rearwardly-extending web provided with a cam-face extending to the surface of the core when the wing is in its operative position, and a permanently-located 130 bearing-roll arranged contiguous to the fixed abutment of the engine-cylinder, to traverse

the cam-face of the piston-web and allow the gradual extension of the wing after passing the abutment, substantially as specified.

3. In a rotary engine, the combination with 5 a casing having a fixed abutment, and a rearwardly-extending piston-wing-repressing cam, and valve mechanism for controlling the inlet and exhaust of motive agent, of a piston-core, piston-wings mounted upon said 10 core for radial extension and provided with attached rearwardly-extending webs 13 having diagonally-disposed outer cam-faces for traversing a bearing-roll in the plane of said fixed abutment, and equal in radial extent to 15 the interval between the surface of the core and the wall of the casing, and extending-springs arranged respectively under the piston-wings and their webs, substantially as specified.
- 20 4. In a rotary engine, the combination with a casing provided with spaced inlet and exhaust ports, and valve mechanism for controlling the admission of motive agent to the

inlet-port, a fixed abutment and a rearwardly-tapered piston-wing-repressing cam, and a 25 bearing-roller at the apex of said abutment, of a piston having a core and yieldingly-extended wings having rearwardly-projecting cam-faced webs for coöperation with said repressing-cam and roller, and an adjustable 30 relief or gage cock communicating with the steam-chamber of the cylinder between said fixed abutment and the exhaust-port, whereby the back pressure upon a piston-wing after passing the exhaust-port, may be regulated to prevent back pressure past said roller, 35 substantially as specified.

In testimony that we claim the foregoing as our own we have hereto affixed our signatures in the presence of two witnesses.
